Primary Examiner — T Chase Nelson*Assistant Examiner* — Jonathan J. Han(74) *Attorney, Agent, or Firm* — Katten Muchin Rosenman LLP(57) **CLAIM**

The ornamental design for the ladder cart, as shown and described.

DESCRIPTION

FIG. 1 is a front perspective view of a ladder cart of the present invention;

FIG. 2 is a back perspective view of a ladder cart of the present invention;

FIG. 3 is a first side view of a ladder cart of the present invention;

FIG. 4 is a second side view of a ladder cart of the present invention;

FIG. 5 is a frontal view of a ladder cart of the present invention;

FIG. 6 is a back view of a ladder cart of the present invention; and,

FIG. 7 is a top view of a ladder cart of the present invention. The broken lines in the figures are used to show unclaimed environment and form no part of the claimed design.

1 Claim, 6 Drawing Sheets(56)
